MULTI-POSITION ELECTRICAL SWITCH

Russell Brooks, Towson, Md., assignor to The Martin Company, a corporation of Maryland

Application October 24, 1956, Serial No. 618,020

9 Claims. (Cl. 200—6)

This invention relates to a multi-position electrical switch, and more particularly to a switch of the wobble disc contact type.

In many electrical systems it is desirable to provide a single switch which is capable of making and breaking a variety of different electrical circuits with extreme rapidity. In most circumstances in which such characteristics are desirable, it is also desirable for the switch to be as compact as possible, and sealed in such a manner as to insure against interferences with operation due to the entrance into the switch body of moisture, dust or other contaminating matter. Previous attempts to satisfy the need for such a switch have been switches which if sufficiently compact and capable of a large enough number of contact positions, could not be operated rapidly, did not engage and disengage the various contacts with definiteness, and could not pass rigorous humidity tests.

In many instances, it is very important for a multi-position electrical switch of this type to have definite operating characteristics in all positions, for the switch operator's attention may be concentrated on something other than the operation of a switch. As an example, the operator may be watching a display upon a cathode ray tube, such as may be used in conjunction with a radar set. In such an instance, it is most important that the switch have distinct feel characteristics so that the operator will be enabled to detect the making or breaking of a particular circuit, and to be cognizant at all times of the exact position of the contacts of the switch. Existing switches of the multi-position type have been found to require high operating forces with attendant slow speed operation, to lack satisfactory feel characteristics, and generally to be somewhat limited in the manner in which the operating lever of the switch can be moved from one operating position to another.

It is, therefore, a principal object of this invention to provide a multi-position electrical switch which enables a variety of electrical contacts to be rapidly engaged and disengaged in a definite, snap action manner.

It is another object of this invention to provide a multi-position electrical switch which, because of the relatively small forces required to manipulate the operating lever of the switch, and other constructional advantages possesses very sensitive feel characteristics.

It is still another object of this invention to provide a multi-position electrical switch in which substantial force is exerted in engaging and disengaging its various contacts, but in which the sensitivity of the operating lever can be varied to meet individual needs.

It is a further object of this invention to provide a multi-position electrical switch in which the operating lever can be rapidly moved from one contact position to another without it being necessary each time for the operating lever to be moved through a neutral point.

It is a still further object of this invention to provide a multi-position electrical switch which is compact, simple in design, and which is sealed so that it will operate

2

satisfactorily without electrical failure under extreme environmental conditions, including high humidity.

A multi-position electrical switch constructed according to this invention comprises a central distribution contact and at least three fixed electrical contacts arranged in a spaced array about the distribution contact. The distribution contact has at least six flat side edges, with alternate side edges aligned with the fixed electrical contacts. A wobble disc is located upon the distribution contact, and is arranged to tilt upon any of the flat side edges. The wobble disc is equipped with a flange overlying and normally spaced from the fixed contacts, and means are provided to selectively tilt the wobble disc upon a flat side edge to bring the flange into operative engagement with at least one of the fixed electrical contacts. The disc, when tilting upon one of the alternate side edges that is aligned with an electrical contact, is brought into operative engagement with only that contact, and when tilting upon a side edge intermediate two of the alternate side edges is brought into operative engagement with two fixed electrical contacts.

An operating lever may be employed to move the wobble disc to the positions desired, and the lever is equipped with a spring urged plunger that is biased into firm engagement with the wobble disc, thereby to bias the lever and wobble disc to a neutral position in which the wobble disc is out of engagement with the fixed contacts. Because of this wobble disc bias and tilt arrangement, the wobble disc has a definite snap action as the operating lever is moved to and from each position.

A guide plate is preferably provided adjacent the operating lever, and a number of lever-receiving recesses are provided in the guide plate. The positioning of the recesses is related to the positioning of the fixed electrical contacts, and are of a number equal to the number of the fixed contacts. While the operating lever is freely movable between its various operating positions, the guide plate is nevertheless effective to stabilize the operating lever in certain operating positions, so that the wobble disc is stabilized in each operating position either by being in engagement with two electrical contacts, or because the operating lever is in engagement with a recess in the guide plate.

Further objects and advantages of this invention will be more readily apparent from the following description, when read in connection with the accompanying drawings in which:

Figure 1 is an elevational cross sectional view of the switch;

Figure 2 is a top plan view of the distribution contact;
Figure 3 is a side elevational view of the distribution contact;

Figure 4 is a sectional view taken along line 4—4 of Figure 1; and

Figure 5 is a diagrammatic view showing the relation of the guide plate to the fixed contacts arrayed about the centrally disposed distribution contact, and revealing symbolically the manner in which contact is made between the centrally disposed distribution contact and either a single fixed contact, or simultaneously with two fixed contacts.

The switch according to this invention includes a distribution contact 5 and fixed electrical contacts 1, 2, 3 and 4 placed in a spaced array about the distribution contact. In the illustrated arrangement, the contacts are preferably located on one end 7' of a hollow housing 7 that may be cylindrical in shape, and open at the other end. The housing 7, including end portion 7' is preferably made of plastic or other non-conducting material, and the contacts are in sealed relation to the housing. A peripheral flange 8 is formed about the upper surface

of distribution contact 5, and as illustrated in Figs. 2 through 4, the peripheral flange 8 has a number of flat side edges 8'. As revealed in Figure 4, alternate side edges 8' are placed in aligned relation with the fixed contact points 1, 2, 3 and 4, while the side edges intermediate the alternate side edges are in alignment with points that would be midway between any two fixed contacts. While the preferred embodiment shows eight side edges and four fixed contact points, it is to be understood that six side edges and three contact points, or another even number of side edges and half as many contact points could be successfully employed in accordance with this invention.

A wobble disc 6 is mounted upon the distribution contact 5 in such a manner that it can be pivoted or tilted upon a flat side 8' into engagement with any of the fixed contacts, including simultaneous engagement with any two adjacent contacts. A planar portion 6' on the underside of the wobble disc is in direct contact with the peripheral flange 8 of the distribution contact, so as the wobble disc is tilted, the planar portion will pivot upon one of the side edges 8'. Because the side edges 8' are aligned with the fixed contacts, the wobble disc is automatically guided into engagement with the contact or contacts desired. A lower hub 9 is centrally provided on the lower surface of wobble disc 6, and this hub fits within a recess 5' located in the upper surface of distribution contact 5. This insures the correct positioning of the wobble disc in the desired location atop the distribution contact. The hub 9 is undercut to a diameter sufficiently less than the inner diameter of recess 5' that the disc 6 can be freely moved with respect to the distribution contact, into engagement with any of the fixed contacts.

The wobble disc 6 extends upwardly and outwardly from its central portion in somewhat of a conical manner, and on the underside of the periphery of the disc is a metallic contact ring or flange 10 that extends entirely about the periphery of the disc. The flange 10 overlies the fixed contacts 1 through 4 and is normally spaced therefrom, but as the wobble disc is tilted, the flange 10 will be moved into electrical engagement with any contact, or into simultaneous engagement with two adjacent contacts.

An operating lever 15 is mounted in housing 7 directly above wobble disc 6, so that the disc may be moved into the desired position of engagement with the fixed contacts.

An enlarged or ball shaped portion 14 is provided on the operating lever adjacent the end of the lever nearest the wobble disc 6. This ball shaped portion is rotatably mounted in ball socket 28, which is created between ball retainers 12 and 13. The ball retainers are closely fitted into the upper or open end of the housing and an encircling shoulder 27 is provided on the inner surface of the side of the housing to form a support for the ball retainers. The lever 15 is universally movable in ball socket 28, and as it is moved in one direction, this causes a countermotion of the lower extension 17 of the operating lever, across the fulcrum formed by the ball shaped portion in ball socket 28. Therefore, by appropriate movements of the operating lever, the wobble disc may be moved freely into any position desired. An operating button 16 is provided on the upper end of the operating lever 15, and this button is maintained in the desired location by means of a suitable set screw 16'.

The surface of wobble disc 6 opposite the hub 9 is provided with a conical socket 11, which may be arcuate but which is preferably substantially parabolic as shown. A plunger 19 of hard plastic or other insulating material is slidably mounted in a suitable recess in extension 17, and is biased by compression spring 18 into firm engagement with socket 11. Because of the spring biased plunger and its interaction with the socket 11, when the operating lever is released, it will center as shown in Fig. 1 to hold the wobble disc 6 in the flat, centered position in which it is out of engagement with all of the fixed

contacts. When the operating lever is manipulated to one of its angular operating positions, the plunger 19 will ride up on the concave surface of the conical socket 11, and will cause the wobble disc to be tilted upon one of the flat side edges 8' so that the flange 10 will be brought into engagement with one or more of the fixed contacts. At this time, a selected circuit will be completed to effect the desired operation.

It is to be noted that when the operating lever has been moved to a deflected position, the spring 18 is compressed to a greater extent than when the switch is in its centered position. This compression of the spring causes the wobble disc to be held against the selected contact or contacts with relatively high pressure, which insures good electrical contact with a minimum chance of arcing. It is also to be noted that with this construction, a snap action of the disc is produced both during the making and the breaking of a circuit, due to the fact that the wobble disc will tilt sharply upon a flat side edge 8' in one direction or the other as soon as the line of force exerted by plunger 19 crosses the edge upon which the wobble disc is tilting.

To insure stability for the switch when the operating lever 15 has been moved to bring the wobble disc into engagement with a single fixed contact, a guide plate 21 is provided in the upper portion of the housing 7, and an aperture 22 is located in the central portion of the guide plate, through which the operating lever 15 extends. The aperture 22 is formed in such a manner as to provide a number of lever-receiving recesses 22', the number of recesses being dependent upon the number of fixed contacts, and in this instance being four in number.

These recesses 22' are placed in a definite orientation with respect to the fixed contacts, and inasmuch as the operating lever 15 moves in the opposite direction to the direction of the contact with which the wobble disc is making engagement, the recess that corresponds to a particular fixed contact is located 180° away from that contact. In other words, referring to Fig. 5, if the operating lever 15 is moved into any of the cardinal positions A, C, E or G, the wobble disc will be caused to tilt into engagement with fixed contacts 3, 4, 1, or 2, respectively. 35

Also indicated on the guide plate 21 are the intermediate positions B, D, F and H. When the operating lever has been moved to one of these positions, the wobble disc is caused to be moved into engagement with two fixed contacts simultaneously. A study of Fig. 5 will reveal the various contact relationships that can be obtained by the use of the present switch. As an example, when the operating lever has been moved into position 45 H, the wobble disc 6 moves so as to bring contacts 2 and 3 into electrical engagement with the distribution contact 5, as is indicated in the lower right-hand corner of Fig. 5.

The construction of the wobble disc-contact arrangement is such that by maintaining his finger on the operating button 16, the operator can sense the position of the wobble disc at all times. When the operating lever has been moved to an intermediate position so as to cause the wobble disc 6 to tilt upon an intermediate edge 8', the flange 10 comes to rest upon two fixed contacts, thereby to form a "tripod." The bias of plunger 19 is sufficient that the wobble disc will be moved to and from this tripod configuration with quite a bit of definiteness, which is responsible for the fact that the operator can feel such movements of the wobble disc. This construction, in conjunction with the provision of the guide plate for guiding the operating lever when it is desired to engage a single contact makes it possible for the operator to move the switch into any and all of the positions desired without any substantial amount of concentration on the operation being necessary. Furthermore, the operating lever need not be returned to the center or rest position each time, for the switch can be moved from one position to another, or even through all eight 70 positions seriatim without it being necessary to cause

the operating lever to pass through the position indicated in Fig. 1.

Since it is understood that different operators will have varying desires as to the sensitivity of the switch, according to this invention the operator may adjust the compression of spring 18 so that the wobble disc will be caused to engage and disengage the fixed contacts with a desirable amount of force. To this end, a centrally disposed adjustment screw 20 is provided in the central portion of operating lever 15, and since this screw is in operative relation to the upper portion of spring 18, by adjustment of screw 20, the spring 18 may be adjusted to the desired amount of compression.

Suitable sealing arrangements are provided so that the switch according to this invention will be "environmentally free." As previously mentioned, the contacts in the bottom 7' are in sealed relation and ball retainer 13, which rests upon shoulder 27 located around the interior of the housing 7, is provided about its periphery with an O-ring 31. Suitable grooves or recesses are provided on the periphery of retainer 13 and on the interior of the housing so that the O-ring can be seated very tightly. Further, a seal 26 is provided about the periphery of retainer 12, and a cup shaped resilient seal or boot 23 is provided intermediate retainer 12 and guide plate 21. The central portion of boot 23 is provided with an aperture to receive the operating lever 15, and the boot is preferably sealed to the lever, such as at point 24.

The guide plate 21 may be maintained in the desired position in the upper part of the housing by means of two or more screws (not shown) that extend radially inward through the cylindrical walls of the housing and threadedly engage suitable threaded holes provided on the periphery of plate 21. Preferably these switch components are so arranged that the lower flange 30 of boot 23 will be tightly compressed between the upper face of ball retainer 12 and the lower face of guide plate 21 at point 25 to provide a good seal. In addition to sealing the operating lever against the entrance of moisture into the switch, the boot 23 prevents undesirable rotation of the operating lever 15 about its axis, for the boot 23 would become "wound up" when such rotation tended to take place.

The ball socket 28 and the ball 14 are preferably provided with an aluminum alloy hardcoat and lubricated by a suitable application of molybdenum disulfide or molybdenum disulfide in a resin binder. This method of lubricating eliminates the need for any further lubrication during the normal period of the usefulness of the switch.

To facilitate the attachment of an electrical conductor to the distribution contact 5, a suitable fitting such as a screw 32 may be provided on the underside of this contact. The lower portions of the fixed contacts 1 through 4 preferably extend below the bottom 7' of the housing, and similar fittings are provided on these lower portions so that all of the contacts of the switch can be electrically connected to the circuitry in which the switch is to be used.

In the operation of this switch, the operator moves the button 16 in the direction of one of the eight positions indicated on the guide plate. The motion of the operating lever causes a resulting countermotion of the extension 17 across the fulcrum formed by ball 14 rotating in ball socket 28. This countermotion causes the plunger 19 to move away from the center of the conical socket 11, located in the upper portion of wobble disc 6, and to ride up on the concave surface of the socket. When the line of force passes the edge of peripheral flange 8, the wobble disc is caused to pivot or tilt upon a flat edge 8' until the flange or peripheral area 10 of the disc comes to rest on two fixed contacts in a "tripod" arrangement or comes into engagement with a single contact. The particular engagement with the fixed contacts, of course,

depends upon the position into which the operating lever is moved. When the wobble disc is moved into engagement with a single fixed contact, because of the presence of guide plate 21, one of the recesses 22' is available to stabilize the operating lever 15, and this in turn causes the wobble disc to be stabilized in its tilting about the flat edge 8' that is aligned with a single contact.

This construction in which flat undersurface 6' of the wobble disc pivots upon the flat sides 8' of the peripheral flange 8, in conjunction with the spring biased plunger arrangement provides a snap action of the switch as it is moved into the position desired. When in an operating position, the wobble disc 6 provides a good current path between the distribution contact and the fixed contact or contacts engaged by the peripheral flange 10.

When the button is released, the plunger 19 tends to return to the bottom of the concave socket 11, in which position the spring 18 is in a less compressed state. This causes the wobble disc to be snapped back into the neutral position, with a minimum of arcing taking place between the peripheral flange and the fixed contact or contacts.

Modifications of the present invention will be apparent to those skilled in the art, but it will be understood that such modifications are within the true purposes and the scope of the following claims.

I claim:

1. A multi-position electrical switch comprising a distribution contact, at least three electrical contacts arranged in a spaced array about said distribution contact, said distribution contact having at least six flat side edges, with alternate side edges aligned with said electrical contacts, a wobble disc located upon said distribution contact and arranged to tilt upon any of said flat side edges, said wobble disc having a flange overlying and normally spaced from said electrical contacts, and means to selectively tilt said wobble disc upon a flat side edge to bring said flange into operative engagement with at least one of said electrical contacts, said disc when tilting upon one of said alternate side edges in alignment with an electrical contact being brought into operative engagement with only that contact, and when tilting upon a side edge intermediate two of said alternate side edges, being brought into operative engagement with two electrical contacts so as to provide three point support for said disc.

2. A snap action multi-position electrical switch comprising a distribution contact, at least three electrical contacts arranged in a spaced array about said distribution contact, said distribution contact having at least six flat side edges, with alternate side edges being aligned with said electrical contacts, a wobble disc located upon said distribution contact and arranged to tilt upon any of said flat side edges, said wobble disc having a flange overlying and normally spaced from said electrical contacts, means to selectively tilt said wobble disc upon a flat side edge to bring said flange into operative engagement with at least one of said electrical contacts, said disc when tilting upon one of said alternate side edges in alignment with an electrical contact being brought into operative engagement with only that contact, and when tilting upon a side edge intermediate two of said alternate side edges, being brought into operative engagement with two electrical contacts, and means biasing said wobble disc to a neutral position in which it is out of engagement with said fixed contacts, whereby said switch will have definite snap action as the wobble disc is moved to and from each tilted position.

3. A multi-position electrical switch comprising a central distribution contact having an upstanding peripheral flange with at least six flat side edges spaced therearound, at least three fixed contacts arranged at spaced intervals about said distribution contact, alternate side edges of said peripheral flange being aligned with said fixed contacts, a wobble disc supported by said peripheral flange

and arranged to tilt upon any of said flat side edges, said disc having a peripheral area overlying and normally spaced from said fixed contacts, an operating lever arranged to engage said disc to selectively tilt said disc upon a flat side edge of said distribution contact so as to bring said peripheral area into operative engagement with at least one of said fixed contacts, and a guide plate adjacent said operating lever, said guide plate having a number of lever-receiving recesses therein, the positioning of said recesses being related to the positioning of said fixed contacts and being of a number equal to the number of said fixed contacts, said operating lever being freely movable between all operating positions, and being stabilized by said guide plate when being operated so as to cause said wobble disc to tilt upon one of said alternate side edges, said disc when tilting upon a side edge intermediate two of said alternate side edges being stabilized by engagement with two of said fixed contacts.

4. A snap action multi-position electrical switch comprising a central distribution contact having an upstanding peripheral flange with at least six flat side edges spaced therearound, at least three fixed contacts arranged at spaced intervals about said distribution contact, alternate side edges of said peripheral flange being aligned with said fixed contacts, a wobble disc supported by said peripheral flange and arranged to tilt upon any of said flat side edges, said disc having a peripheral area overlying and normally spaced from said fixed contacts, an operating lever arranged to selectively tilt said disc upon a flat side edge of said distribution contact so as to bring said peripheral area into operative engagement with at least one of said fixed contacts, said operating lever having a spring urged plunger biased into firm engagement with said wobble disc, said lever and wobble disc thereby being biased to a neutral position in which said wobble disc is out of engagement with said fixed contacts, and a guide plate adjacent said operating lever, said guide plate having a number of lever-receiving recesses therein, the positioning of said recesses being related to the positioning of said fixed contacts and being of a number equal to the number of said fixed contacts, said operating lever being freely movable between its various operating positions, and being stabilized by said guide plate when being operated so as to cause said wobble disc to tilt upon one of said alternate side edges, said disc, when tilting upon a side edge intermediate two of said alternate side edges being stabilized by engagement with two of said fixed contacts.

5. The multi-position electrical switch as defined in claim 4 in which means are provided for modifying the force with which said plunger is biased into engagement with said wobble disc, whereby the sensitivity of operation of said switch can be altered.

6. A multi-position electrical switch comprising a housing, a distribution contact mounted in said housing, said distribution contact having at least six flat side edges, at least three electrical contacts mounted in said housing and arranged in a spaced array about said distribution contact, alternate side edges of said distribution contact being aligned with said electrical contacts, a wobble disc supported by said distribution contact and arranged to tilt upon any of said flat side edges, said wobble disc having a flange overlying and normally spaced from said fixed contacts, and an operating lever projecting into said housing and mounted therein for universal angular movement, said lever being arranged to engage said disc so as to tilt it upon one of said flat side edges of said distribution contact to bring the flange of said wobble

disc into engagement with at least one of said electrical contacts, and a guide plate for said operating lever, said guide plate having a number of lever-receiving recesses therein, the positioning of said recesses being related to the positioning of said electrical contacts in said housing, and being of a number equal to the number of said electrical contacts, said operating lever being stabilized by said guide plate when said lever is being operated so as to cause said wobble disc to tilt upon one of said alternate side edges, said disc when tilting upon a side edge intermediate two of said alternate side edges being stabilized by engagement with two of said electrical contacts.

7. The multi-position electrical switch as defined in claim 6 in which sealing means are provided between said guide plate and said housing, and surrounding said operating lever at the location wherein it projects into said housing, to prevent the entry of dust and moisture.

8. The multi-position electrical switch as defined in claim 6 in which means are provided to prevent dislodgment of said wobble disc from said distribution contact.

9. A snap action multi-position electrical switch comprising a housing, a central distribution contact disposed in said housing, said distribution contact having an upstanding peripheral flange with at least six flat side edges spaced therearound, at least three fixed contacts mounted in said housing and arranged at spaced intervals about said distribution contact, alternate side edges of said peripheral flange being aligned with said fixed contacts, a wobble disc supported by said peripheral flange and arranged to tilt upon any of said flat side edges, said disc having a conical socket centrally disposed on its upper surface, and a peripheral area overlying and normally spaced from said fixed contacts, an operating lever disposed in a location directly above said disc and arranged to selectively tilt said disc upon a flat side edge of said distribution contact so as to bring said peripheral area into operative engagement with at least one of said fixed contacts, said operating lever having a spring urged plunger biased into firm engagement with said conical socket, said lever and wobble disc thereby being biased to a neutral position in which said wobble disc is out of engagement with said fixed contacts, and a guide plate adjacent said operating lever, said guide plate having a number of lever-receiving recesses therein, the positioning of said recesses being related to the positioning of said fixed contacts and being of a number equal to the number of said fixed contacts, said operating lever being freely movable between its various operating positions, said guide plate being effective to stabilize said operating lever when said wobble disc is being pivoted upon one of said alternate side edges, whereby said wobble disc is stabilized in each operating position either by being in engagement with two electrical contacts, or by the operating lever being in engagement with a recess in said guide plate, said switch, because of said wobble disc bias and tilt arrangement, having a definite snap action as the operating lever is moved to and from each position.
